ADJUSTABLE COMBINED ELEVATING AND SUPPORTING DEVICE

Lena M. Baer, Topeka, Kans.

Application May 20, 1936, Serial No. 80,900

1 Claim. (Cl. 248—161)

This invention relates to an adjustable combined elevating and supporting device for a bed and has for its object to provide, in a manner as hereinafter set forth a device of such class that when employed in a set of four arranged in relation to the legs of an ordinary bed, it will convert the latter into a bed of hospital type.

A further object of the invention is to provide, in a manner as hereinafter set forth, a combined bed elevating and supporting means offering a great help to doctors and nurses in caring for patients in the home where the conveniences of the hospital are lacking, as it has been the habit of physicians and nurses in caring for patients in the home to increase the height of the bed by various make-shift methods. The adjustable combined bed elevating and supporting means in accordance with this invention not only overcomes the very troublesome problem of low beds that besets the physician every time he is forced to care for a patient in the home, but further acts as a back-saver for anyone engaged in caring for the sick, more especially in home confinement cases.

Further objects of the invention are to provide, in a manner as hereinafter set forth, a device of the class referred to which is simple in its construction and arrangement, strong, durable, compact, readily installed with respect to the leg of a bed, conveniently adjusted, thoroughly efficient in the use intended therefor, and comparatively inexpensive to manufacture.

With the foregoing and other objects which may hereinafter appear, the invention consists of the novel construction, combination and arrangement of parts as will be more specifically described and are as illustrated in the accompanying drawing wherein is shown an embodiment of the invention, but it is to be understood that changes, variations and modifications may be resorted to which fall within the scope of the invention as claimed.

In the drawing:

Figure 1 is a perspective view of a bed illustrating it as being supported in an elevated position by a set of adjustable combined elevating and supporting devices in accordance with this invention.

Figure 2 is a perspective view of the device illustrating it in position for supporting a leg of the bed. The lower portion of the leg is shown and the castor on the lower end of the leg is illustrated in dotted lines housed within the upper portion of the device.

Figure 3 is a top plan view of the device, and

Figure 4 is a side elevation partly in section. With reference to the drawing, a bed is designated at 5 and its legs at 6. The lower end of each leg carries a castor wheel 7 as indicated in dotted lines Figure 2.

An adjustable combined bed elevating and supporting device in accordance with this invention includes a base 8 which may be hollow or solid and is illustrated by way of example as hollow and open at its bottom. The base 8 may be of any suitable contour, preferably, it will be circular and is so shown. The body of base 8 at its top is formed with an axially arranged threaded opening 9 and an upstanding interiorly threaded collar 10 having its inner face forming a threaded continuation of the threaded wall of opening 9.

The device includes a tubular pedestal 11 of the desired height formed with an elongated slot 12 disposed lengthwise and intermediate the ends thereof. The body of pedestal 11 is also provided with superposed circumferentially extending bayonet-shaped slots 13 which open at one end into one side of slot 12 adjacent the ends of the latter. The number of slots 13 may be as desired and by way of example only two are shown. The pedestal 11 at its lower terminal portion is formed on its outer periphery with a group of threads 14 for engagement with the threads of the wall of opening 9 and the threads of the collar 10 whereby base 8 and pedestal 11 are anchored together.

The device includes an upstanding vertically adjustable supporting element 15 which is disposed in telescopic relation with respect to the pedestal 11. The element 15 is formed of a solid shank 16 of the desired length provided adjacent its lower end with a laterally disposed stud 17 for coaction with a selected slot 13 for the purpose of coupling the element 15, in its adjusted position to pedestal 11, as well as for supporting and latching element 15 in such position. The slot 12 provides a clearance for stud 17 when shifting shank 16 lengthwise of pedestal 11. Formed integral with the upper end or head part 18 of the shank 16 is a hollow extension 19 of segmental contour which provides a segmental shaped socket 20 of less width than that of the head part 18. The extension 19 extends laterally in opposite directions with respect to head part 18. The mouth of socket 20 is of rectangular contour in plan. Integral with the upper end of and extended laterally in all directions, with respect to extension 19 is an annular cup 21 having a rectangular slot 22 in and diametrically of its bottom. The marginal portion of the bottom of

cup 21 is rounded. The cup 21 is of greater height than extension 19. The walls of slot 22 are flush with the walls of the socket 20 whereby communication is established between the cup and socket. The cup and socket are to receive the castor fitting 23 at the lower end of a leg of the bed. The socket 20 is to receive the castor wheel 7 when the device is in bed elevating and supporting position.

5 The manner of constructing the device provides for positioning a bed at different heights. Owing to the manner in which the pedestal, base and shank are connected together when the device is set up, the latter may be conveniently 10 disassembled when occasion requires.

10 Although the device is designed primarily for use in elevating and supporting beds, it is to be

understood that it is for employment in any connection for which it is found applicable.

What I claim is:

In an adjustable combined elevating and supporting means for a bed of the post type, an upstanding unit for receiving and supporting each post, said unit consisting of a base, a vertically adjustable standard anchored to the base, an open top combined castor wheel structure receiver, support and retarder element of segmental contour carried by the upper end of the standard, and an annular cup having its bottom formed with a diametrically disposed rectangular opening, said element being integral with the bottom of the cup and having its inner face 15 registering with the edges of said opening.
